UNITED STATES PATENT OFFICE.

WILLIAM T. BLACKWELL, OF WESTFIELD, NEW JERSEY, ASSIGNOR TO WESTINGHOUSE LAMP COMPANY, A CORPORATION OF PENNSYLVANIA.

DESIGN FOR A SHADE FOR LIGHTING-FIXTURES.

59,576.

Specification for Design.

Patented Nov. 8, 1921.

Application filed March 30, 1921. Serial No. 457,065. Term of patent 7 years.

To all whom it may concern:

Be it known that I, WILLIAM T. BLACKWELL, a citizen of the United States, residing at Westfield, in the county of Union and State of New Jersey, have invented a new, original, and ornamental Design for Shades for Lighting-Fixtures, of which the following is a specification, reference being had to the accompanying drawing, forming part thereof.

The single figure is a side elevational view of a shade for lighting fixtures, showing my new design.

I claim:

The ornamental design for a shade for lighting fixtures, as shown.

WILLIAM T. BLACKWELL.
